WIDENED KNITTED FABRIC AND METHOD OF MAKING THE SAME

Otto F. Smetana, Concord, N. C., assignor, by mesne assignments, to Phil Cord Corporation, a corporation of North Carolina

Application December 4, 1950, Serial No. 199,049

12 Claims. (Cl. 66—189)

My invention is a weft knit, selvaged fabric forming a blank of varying width particularly adapted for the manufacture of full-fashioned hosiery, and having one or more widened sections characterized by the outward transfer of an end needle loop at one end only of each of certain courses and by the addition of a sinker loop adjoining the transferred needle-loop. Such transferred needle-loop and sinker loop preferably provide base loops for the subsequent knitting of needle wales lying outwardly from but parallel with the previously knit selvage loops of a previously knit fabric section.

My invention also includes the method of forming and transferring to effect widening of such fabric during the knitting thereof on the usual Cotton type of full-fashioned hosiery machine.

When a course of a usual selvaged weft-knit fabric knit from a continuous yarn is of the same width as an immediately preceding course, the selvage loops at the opposite ends of each course differ from one another in accordance with the direction in which the yarn is drawn in laying the course: viz., the selvage loop at the draw edge, or edge from which the yarn is drawn, consists of a simple needle loop having only two legs, whereas the selvage loop at the lead edge, or edge toward which the yarn is drawn, consists of a needle loop and a sinker loop intertwined therewith and formed by a section of the yarn lead drawn through the end needle loop to connect it with the simple needle loop forming the selvage loop of the next succeeding course. Consequently the selvage loops at the same edge of consecutive courses of ordinary fabrics are alternately plain loops and loops including a twist of sinker loop.

It has been proposed to change the width of weft-knit fabric by widening consecutive courses respectively adjacent to opposite selvages by extending the lay of the yarn lead in the draws of the yarn in opposite directions for the respective courses, and it has also been proposed to widen fabric by transferring outwardly loops at both ends of one or more courses. But such widenings are difficult in practice and not altogether satisfactory in result and have heretofore precluded the formation of fabric having fast selvages and adjacent lace work.

In accordance with my invention, weft knit fabric is widened by outwardly transferring an end needle-loop at the lead end of a course, viz., adjacent to the yarn lead, and by adding a loop adjacent to the transferred loop. The added loop is preferably formed by forming a distinct sinker loop from the yarn lead section which would ordinarily be twisted around the leg of the terminal needle loop at the lead edge of the course. Consequently, one selvage of each widened course of the fabric will contain a juxtaposed plain transferred loop and an added loop, but successive courses will be widened only at opposite selvages. The transferred loop of one selvage is staggered with respect to the transferred loop of the other selvage, and the added loop in one selvage of one course may partly overlay the next course, which may, or may not, have an added loop in the other selvage.

2

The transfer of loops is preferably effected by lace points (Petinet points) mounted at opposite ends of a reciprocable lace rod which may be journaled in bearings of a usual narrowing machine so that the points may be swung downward into active position when the regular narrowing point units are racked outwardly beyond the needle section or may be swung upward into inactive position when the regular narrowing points are to be used in fashioning the stocking.

- 5   10   15   20   25
- 10   The distance between the lace points on the lace rod is greater than the width of the fabric, so that loops along one selvage of the fabric may be transferred outwardly without any interference of the lace point at the opposite ends of the rod with the fabric, and vice versa.
- 15   The lace points at the opposite ends of the rod may also be used, if desired, in alternation to form lace stitches inward from the selvages to provide ornamental designs in the body of the fabric adjacent to its widened section having fast selvages.
- 20   The additional loop at the end of a course is preferably formed on the next traverse of the yarn by bending the lead around an extra needle beyond the transferred terminal needle loop of such course.

25   The positioning of the lead for bending around the extra needle to form a sinker loop is effected by moving the usual yarn carrier stops of the knitting machine each outward a distance equal to the pitch of two needles when the main cam shaft is in narrowing position following the completion of knitting of the course to be widened. The carrier rod in action is temporarily connected with and drawn outward by one of the stops so that the yarn tube of each carrier is thereby positioned above the second (instead of the first) divider outward from the needle which knits the end needle-loop to be transferred.

30   35   40   45   50

35   This movement of the yarn tube and the transfer of the end needle-loop gives the yarn lead extending from the base of such end needle-loop to the feed tube such an angle as to bring it in front of an additional needle and under the sinkers and dividers during the usual movements of the needles, sinkers and dividers while the main cam shaft is in its narrowing position. The next traverse of the yarn carrier therefore bends the lead around the extra needle and forms a bight thereon beyond the transferred end needle-loop.

55   60   65   70

50   Such traverse continues beyond the needle holding the selvage loop of the opposite side of the fabric and until the feed tube reaches the second (instead of the first) divider beyond such needle. The last laid yarn is knit into a course.

55   60   65   70

55   The main cam shaft is then shifted to "narrowing" position, and the narrowing machine operated to transfer the end needle-loop adjacent to the lead outward one needle, but without shifting the carrier stops. The lead from the transferred loop to the carrier tube had such an angle that the movements of the needles, sinkers and dividers while the main cam shaft is in "narrowing" position causes the lead to be under the sinkers and dividers and in front of the needle outward from the transferred loop. Hence, the lead will be bent around such outward needle to form a sinker loop upon the next traverse of the yarn carrier to lay a new course.

65   70   75   80

65   As the narrowing points are racked outward during widening, the lace (Petinet) points may be used for making designs as well as transferring end needle loops outward.

70   75   80   85

70   The principles of my invention and the best mode I have contemplated of putting it into practice will further appear from the following description and the accompanying drawings in illustration thereof.

75   80   85

75   In the drawings, Fig. 1 is a diagrammatic, perspective view of a full-fashioned stocking widened in accordance

with my invention forwardly of the heel narrowing; Fig. 2 is a diagrammatic, plan view of the foot section of a hosiery blank for making the stocking of Fig. 1; Fig. 3 is an enlarged, fragmentary, diagrammatic view of a portion of the blank shown in Fig. 2 within the area indicated by dot and dash lines; Fig. 4 is an enlarged, diagrammatic fragmentary view of selvaged areas of a portion of a widened section shown in Fig. 3; Fig. 5 is a diagrammatic view of a needle bar and lace bar of a conventional full-fashioned hosiery machine of the Cotton type; Fig. 6 is an enlarged, diagrammatic view illustrating the stitch construction of part of the fabric sections such as shown in Fig. 4, the lower courses beginning at about the position indicated by the line 6—6 of Fig. 1; Fig. 7 diagrammatically illustrates movements of the carrier stops, yarn carrier and a lace point and the transfer of loops by a lace point in forming the first widened course; Fig. 8 is a fragmentary, diagrammatic, transverse, sectional view taken approximately on the line 8—8 of Fig. 7 and indicating the laying of a yarn lead when the yarn carrier is moved outward by movement of a carrier stop during a widening cycle; Fig. 9 diagrammatically illustrates the laying and sinker-kinking of a length of yarn to be drawn through the first widened course to form a second widened course; Fig. 10 diagrammatically illustrates the dividing of the 25 yarn laid in Fig. 9; Fig. 11 diagrammatically illustrates the fabric after loops have been drawn through the first widened course and certain loops of the second course have been transferred outwardly; Fig. 12 diagrammatically illustrates the laying and sinker-kinking of a further 30 length of yarn along the loops of the second widened course; Fig. 13 diagrammatically illustrates the dividing of the yarn laid in Fig. 12; Fig. 14 diagrammatically illustrates the fabric after the yarn laid in Fig. 12 has been drawn through the loops of the second widened course to 35 form a third course and one of the newly drawn loops has been transferred to form a lace stitch located inward from the selvage; Fig. 15 diagrammatically illustrates the fabric after a new course of loops has been drawn through the fell loops of Fig. 14 and one of the newly formed loops remote from the selvage has been transferred to form a lace stitch; and Fig. 16 diagrammatically illustrates the fabric after a new course of loops has been drawn through the fell loops of Fig. 15, and one of the loops of the last formed course located remote from the 40 selvage has been transferred; and Fig. 17 diagrammatically illustrates the fabric after a new course of loops has been drawn and one of them transferred, the fabric and parts being now ready for the repetition of the cycle begun with the laying of the top course of Fig. 7.

For the purpose of illustrating my invention, I have shown in the drawing a woman's full-fashioned, single unit stocking having a usual welt W, a diaphanous leg and instep portion L, a reinforced heel portion H, a reinforced foot portion F and a reinforced toe portion T. The heel section H may be widened out in any desired manner to form a pocket and the fabric is then narrowed between the heel and sole by a row of conventional narrowing marks M.

When the narrowing marks M are of such number and extent as to give a desired fit around the heel and over the instep, they tend to cause the foot section adjacent to the metatarsal arch to be excessively narrow; particularly where the stocking is knit of low denier yarn on a fine gauge machine, and a leading object of my invention is to facilitate the widening and ornamentation of the foot fabric forwardly of the heel narrowings so as to comfortably accommodate the spread of the foot adjacent to the metatarsal arch.

As illustrated in the drawings, the reinforced foot section F, forwardly of the row of narrowing marks M, is widened out alternately at its opposite selvages by steps f1, f2, f3, f4, f5, f6, f7, f8 etc. The even numbered steps along the right hand selvage are staggered, respectively, relatively to the odd numbered steps along the left hand

5

selvage. If desired, ornamental patterns P may be formed inwardly of the respective selvages by lace stitches p1, p2, p3, p4, p5, p6, p7, p8 etc., extending along, but spaced inwardly any desired distance from the widening steps; such lace stitches preferably extending predominately along a wale at each side of the fabric so as to form parallel lines of lace stitches from which the adjacent edges diverge.

As illustrated in Fig. 6, the stocking blank shown in Figs. 1 to 4, includes loops forming, inter alia, the wales W1 to W17 and courses C1 to C8, the course C1 beginning forwardly of the courses narrowed by the narrowing marks M.

The widening step f1 at the left of the foot blank is formed by the transfer of the end needle-loop NL1 of the course C1 from the wale W11 to the wale W13 and by the sinker loop SL1 which connects the needle loop NL1 with the loop NL3 of the course C2. The lace stitch p1 is formed by the transfer of the needle loop NL5 of the course C1 from the wale W3 to the wale W5.

The widening step f2 at the right hand selvage of the foot blank is formed by the transfer of the needle loop NL2 of the course C2 from the wale W12 to the wale W14 and by the sinker loop S12 which connects the needle loop NL2 with the loop NL4 of the course C3. The lace stitch p2 is formed by the transfer of the needle loop NL6 of the course C2 from the wale W6 to the wale W8.

From the foregoing it will be seen that the steps f1 and f2 each widen the foot fabric a distance of two needles on opposite sides of the fabric in alternation, and that each widening step results from the outward transfer of an end needle loop and the formation of a sinker loop connecting such transferred loop with a needle loop of a subsequent course of loops.

Preferably the courses C3, C4, C5 and C6 are then knitted of the width to which the fabric has been widened by the alternated steps f1 and f2, and such uniform width courses may have loops thereof transferred for the formation of further elements of the ornamental designs P. For example, the needle loop NL7 of the course C3 may be transferred from the wale W7 to the wale W9; the needle loop NL8 of the course C4 may be transferred from the wale W2 to the wale W4; the needle loop NL9 of the course C5 may be transferred from a wale (not shown) to the wale N1 and the needle loop NL10 of the course C6 may be transferred from the wale W12 to the wale W14.

It will, of course, be understood that, in practice, the transferred loops NL5, NL6, NL7, NL8, NL9, etc., forming lace stitches of the patterns P would be a greater number of wales inward from the selvages than is diagrammatically shown in Fig. 6 and that a lace design of any desired form may be made by suitably shifting needle loops from one wale to another remote from the selvage in various courses of the fabric between the beginning and end of widening. The production of the design P as shown merely requires the transfer of needle loops from the wale W3 to the wale W5 and the transfer of needle loops from the wale W6 to the wale W8 in a sequence of alternating courses and the sagittal top of the design would be produced by a reverse shifting of loops as described in connection with the lace stitches p1 to p6.

The widening cycle is again begun in course C7 to form the widening step f3, and is repeated as often as is required to give the desired width to the fabric adjacent to the metatarsal arch.

An important feature of my invention is that my method may be practiced and the fabric produced upon standard Cotton types of full-fashioned knitting machines by appropriately positioning controlling buttons on pattern chains thereof and appropriately positioning transfer points P1 and P2 on a lace bar LB, or other transfer rod, controlled by the narrowing machine (not shown) of a standard knitting machine.

Such narrowing machines are provided with spindles and ratchet mechanisms for moving the carrier rod stops CS1 and CS2 at desired intervals, in or out a distance equal to the pitch of two needles so as to cause the stoppage of a yarn carrier YC above a divider (dividing sinker) located outwardly from the needle forming selvage loops of a selvage of the fabric being knit.

In the operation of the machine, a yarn carrier lays yarn Y along a bank of en masse movable needles, including needles N1 to N18, and yarn so laid is kinked by sinkers, including jack sinkers s3, s4, s7, s8, s11, s12, s15, s16, and divided by dividing sinkers or dividers d1, d2, d5, d6, d9, d10, d13, d14, d17 and d18.

For simplicity only a single main yarn carrier YC is shown, but the usual splicing carriers for laying reinforcing yarns may, of course, be moved in the same manner as the carrier YC.

As indicated in Fig. 7, the loops of a course C1 of fabric was initially knit on the needles N1 to N12, and, during such knitting, the yarn carrier YC was held in position above the divider d13 by the carrier stop CS1. With the carrier YC so positioned, the lead of the yarn Y extended through the bight of the selvage loop of the preceding course and between the needles N13 and N15 to the tube of the yarn carrier YC, as indicated in dotted lines.

At the conclusion of the knitting cycle forming the course C1, the main cam shaft of the knitting machine was shifted lengthwise into the "narrowing" cycle to bring the narrowing machine into operation and permit the control buttons of its pattern chain to cause the rotation of the usual spindles to move outward the carrier stops CS1 and CS2 from positions for stopping yarn carriers above the dividers d13 and d14 to positions for stopping carriers above the dividers d17 and d18.

The yarn carrier CS1 was connected in the usual manner with the yarn carrier YC so that the outward movement of the yarn carrier stop CS1 moved the yarn carrier YC outward from the divider d13 to the divider d17, thereby laying a lead of the yarn Y along the knock-over bits K while the sinkers and dividers are retracted and the top of the needles are in a position below the tops of the knock-over bits. As the needles rise in the "narrowing" cycle, they move toward the press face PF of the sinker bed and the noses of the sinkers are advanced. The angle of the lead of the yarn Y between the tube of the yarn carrier YC and the selvage loop of the preceding course is such that the needle N15 rises in back of the lead, so that the lead passes between the needles N15 and N17 and beneath the nib of the sinker S15 as indicated in full lines in Fig. 9.

Meanwhile, the lace bar LB has been operated by the narrowing machine, under control of buttons on the pattern chain, to cause the Petinet point P1 to shift the needle loop NL1 from the needle N11 onto the needle N13 and to shift the needle loop NL5 from the needle N3 to the needle N5. The space between the points P1 and P2 is sufficiently great to permit this manipulation by the point P1 without causing the point P2 to engage any of the loops of the fabric.

When the movement of the carrier stops CS1, CS2 and yarn carrier YC, and the shifting of the loops NL1 and NL5 has been completed, the main cam shaft of the machine is again shifted longitudinally into the "knitting" cycle so as to bring the coulier motion into action and move the yarn carrier YC from its position above the divider d17 to a position above the divider d18. This movement of the yarn carrier YC loops the yarn Y around the nib of the sinker S15 and lays it along the beard side of the needles so that the yarn now forms a sinker loop SL1 around the needle N15 and the yarn is kinked by the sinkers between alternate needles, as shown in Fig. 9.

After couloring has been completed, the dividers are advanced by the catch bar in the usual manner to divide the yarn, as shown in Fig. 10, and the kinked and divided

yarn is then drawn by the needles through the loops of the course C1, the loops of which are then cast off excepting the sinker loop SL1 around the needle N15.

Upon completion of the knitting of the course C2 the main cam shaft is longitudinally shifted into the "narrowing" cycle and the lace bar LB is operated by the narrowing machine to cause the Petinet point P2 to shift the needle loop NL2 from the needle N12 onto the needle N14, but without any outward movement of the carrier stops CS1, CS2 or any further outward movement of the yarn carrier YC at this stage of operation. However, during the narrowing cycle, the usual movements of the needles, sinkers and dividers and the angle of the lead of the yarn Y from the base of the transferred loop NL2 to the tube of the carrier YC causes the yarn lead to lie under the sinkers and dividers and in front of the additional needle N16 and to pass between it and the needle N18.

The lace bar LB is also shifted to cause the point P2 to transfer the needle loop NL6 from the needle N6 to the needle N8 so as to form the lace stitch p2.

Upon the next shift of the main cam shaft to "knitting" position, the coulier motion moves the carrier YC from its position over the divider d18 leftward until it is stopped by the carrier stop CS1 over the divider d17. This traverse of the carrier YC loops the yarn lead extending from the base of the transferred loop NL2 around the nib of the sinker S16 and around the needle N16 so as to form a sinker loop SL2 and lay the yarn Y along the beard side of the needles to permit its kinking between every two needles by the advance of the sinkers as shown in Fig. 12.

The yarn Y is then divided by the advance of the dividers, as shown in Fig. 13, and the kinked and divided yarn is drawn by the needles through the loops of the course C2 to form on the needles the loops of the course C3, the sinker loop S12 being meanwhile held on the needle N16, as shown in Fig. 14.

Upon completion of the formation of the loops of course C3, the cam shaft is shifted longitudinally into the "narrowing" cycle, so as to bring the lace bar LB into action and cause the point P1 to transfer the needle loop NL7 from the needle N7 onto the needle N9 so as to form the lace stitch p3. This shifting of the lace bar takes place without any further outward movement of the carrier stops CS1 and CS2.

By the foregoing operations, all the needles, excepting the needles N17 and N18, between the dividers d17 and d18 are now provided with loops, and knitting of courses, of the width of the course C3, may now be carried on for as many courses as desired before repeating the widening cycle.

As illustrated in Figs. 15, 16 and 17, the knitting of courses, of the width of the course C3, is carried on to form the courses C4, C5 and C6 in the usual manner of knitting, excepting that after the knitting of the course C4 the main cam shaft is shifted longitudinally into the "narrowing" cycle to bring the lace bar LB into action and cause the point P2 to shift the loop NL8 from the needle N2 onto the needle N4 so as to form the lace stitch p4; after the knitting of the course C5 the main cam shaft is shifted longitudinally into the "narrowing" cycle to bring the lace bar LB into action to cause the point P1 to shift a needle loop NL9 from a needle (not shown) onto the needle N1 to form the lace stitch p5; and after the knitting of the course C6 the main cam shaft is shifted longitudinally into the "narrowing" cycle so as to bring the lace bar LB into action and cause the point P2 to transfer the needle loop NL10 from the needle N12 onto the needle N14 to form the lace stitch p6.

The widening cycle is then repeated, beginning with the knitting of the loops for the course C7, the movement of the carrier stops CS1 and CS2 each outward a further distance equal to the pitch of two needles, the outward transfer of the left hand end needle loop NL11,

the formation of a sinker loop *SL3* outward from the transferred selvage loop *NL11* and the transfer of a loop from the needle *N3* onto the needle *N5* to form a lace stitch *p7* in walewise alignment with the lace stitch *p1*, all as described in connection with the formation of the course *C1*.

The widening cycles are continued to form the widening steps *f3* to *f8*, and as many more steps as may be desired to give a desired width to the fabric, which, when completed is folded and seamed along the selvages.

It will be noted that the transferred loops *NL1* and *NL2*, and similar succeeding transferred end needle-loops, each initiate or form a starting loop for a new wale positioned outwardly from but extending parallel to the wale containing the selvage loops of the courses preceding the course *C1*. It will further be noted that the sinker loops *SL1* and *SL2*, and subsequent comparable loops, each extend not only along a transferred end needle loop of one course but also along an end sinker loop of the next succeeding course.

Having described my invention, I claim:

1. A weft knit selvaged fabric composed of loops forming courses and wales, and having a widened section, certain courses of said section each having at one end only a needle loop transferred outwardly and initiating a wale positioned outwardly from and parallel to the wale containing the selvage loop of the next preceding course, and a sinker loop extending along at least the full length of a leg of such transferred loop.

2. A weft knit fabric composed of loops forming courses and wales and having a selvaged widened section, said widened section having a course containing at one end only an end needle loop inclined outwardly beyond the selvage needle loop of the immediately preceding course and also including an added loop extending outwardly beyond the selvage loop of the immediately preceding course.

3. A weft knit selvage fabric composed of loops forming courses and wales and having a widened section including in alternating courses end needle loops each transferred outwardly beyond the selvage loop of an immediately preceding course, and an added loop adjacent to each transferred loop and extending beyond the selvage loop of an immediately preceding course.

4. A weft knit selvage fabric composed of loops forming courses and wales, one of such courses having at one end thereof an end needle loop transferred outward beyond the adjoining selvage loop of the immediately preceding course, and said fabric including an added sinker loop contiguous with said transferred loop and extending from said preceding course and along the outside of said transferred loop and along the outside of an end sinker loop of a succeeding course to a course beyond said last named course.

5. A weft knit selvaged fabric widened alternately at opposite selvages by widening steps in staggered relation to one another each of said steps including a transferred needle loop and a selvage loop formed of contiguous sections of the same yarn.

6. In the widening of weft knitted fabric, the steps which comprise knitting a yarn to form a course of loops on a group of the needles of a bank, outwardly transferring an end loop of said course to a needle of said bank beyond said group of needles, bending the lead of said yarn adjacent to said transferred loop around a second needle beyond said group of needles and laying said yarn along and beyond the needles of said group, and knitting said laid yarn through the loops on said needles.

7. In the widening of knitted fabric having a course of loops on a group of the needles of a bank, the steps which comprise knitting a second course of loops through said first named course, transferring outward an end needle loop at one end only of said second course, forming a bight of yarn contiguous with said transferred loop and on the same side of the fabric thereas around a needle

beyond said group, and knitting further courses to form loops through said transferred loop and bight.

8. In the widening of knitted fabric having a course of loops on a group of the needles of a bank, the steps which comprise knitting a course having a needle loop at one end of said group, transferring said needle loop to a needle outward from the needle on which it was knit, forming a sinker loop around a needle adjoining the needle holding said transferred loop, and drawing a loop through said transferred loop while holding said sinker loop on its needle.

9. In the widening of knitted fabric having a course of loops on a group of the needles of a bank, the steps which comprise laying a yarn from a loop in one selvage of said fabric along said group of needles to a point beyond the needle holding a loop in the opposite selvage of said fabric, drawing said yarn through the loops of said first course to form a second course of loops, transferring the end needle loop at one end of said second course to a needle of said bank outward from the needle on which it was formed, bending said yarn around a needle of said bank outward beyond the needle holding the transferred loop to form a bight and laying such yarn along the needles to a point beyond the needle holding the selvage loop at the opposite end of said course, drawing said yarn through the loops of said second course, including said transferred loop, to form a third course while holding said bight on its needle, transferring the end loop of said course opposite said bight to a needle outward from the needle on which it was formed, bending said yarn around a needle of said bank outward from the needle holding the last named transferred loop and laying said yarn along said needles to a point beyond the needle holding said first bight, and drawing said yarn through said third course and through said bight to form a fourth course of loops while holding said second bight on its needle.

10. In the widening of knitted fabric having a course of loops on a group of the needles of a bank of a knitting machine having sinkers and dividers between said needles, a yarn carrier complementary to said needles, and shiftable stops controlling said yarn carrier, the steps which comprise knitting a course of loops through said first course, shifting said stops to permit movement of said carrier to a point adjacent to the second divider beyond the needle holding the selvage loop at either end of said course, moving said carrier to a point adjacent to the second divider beyond the needle holding an end needle loop of said second course and shifting such end needle loop to a needle adjoining the needle on which it was formed, moving said needles to bring an additional needle inside the yarn lead extending from the selvage loop of said first course to said carrier, moving said carrier to form a bight of yarn around said additional needle positioned within said lead and to lay yarn along the loop-holding needles and along three needles beyond the opposite end of the course of loops on said needles, moving said needles, sinkers and dividers to draw said yarn through and cast off the loops on said needles and to position two of said three needles within the lead of yarn extending from the end loop of the cast off course to the carrier, and transferring the end needle loop of the last formed course to one of said two needles.

11. In the widening of knitted fabric having a course of loops on a group of needles of the needle bank of a knitting machine, the steps which include knitting a course of loops through the loops on said group, laying a lead of yarn along additional needles beyond said group and transferring the end needle loop of said second course to one of said additional needles, transferring a loop of the second course from one needle to another of said first named group to form a lace stitch, laying and knitting a yarn to form a bight on one of said additional needles and a new course of loops through the loops of said second course to form a third course and a lead of yarn

70

along additional needles at the opposite end from the additional needles first named, transferring the end needle loop of said third course to one of the additional needles second named, and transferring a loop of the third course from one needle to another of said first named group to 5 form a lace stitch.

12. In the widening and ornamenting of weft knit fabric, having loops forming courses and wales, the steps which include transferring outward in alternation end needle loops at opposite and lead ends of successive 10 courses and transferring other loops of said courses to form lace stitches spaced from the edges thereof.
